UNITED STATES PATENT OFFICE.

WALTER S. BAKER, OF NORMAL, NEBRASKA.

DRINKING CUP.

Application filed August 4, 1924. Serial No. 729,987.

To all whom it may concern:

Be it known that WALTER S. BAKER, a citizen of the United States, residing at Normal, in the county of Lancaster and State of Nebraska, has invented certain new and useful Improvements in Drinking Cups, of which the following is a specification.

This invention relates to new and useful improvements in drinking cups, or containers for other liquids, the primary object of the invention being to form a device of this character of few and simple parts, utilizing as a body therefor a section of an inner tube of an automobile tire, or any other tubular material may be adapted for this purpose.

Still another object resides in providing a device which may be termed a collapsible drinking cup, which may be quickly and readily set up for use, collapsed when desired, and which may be improvised by tourists on the road.

A still further object resides in providing a device which is simple and durable in construction, inexpensive to manufacture, and one which is very effective in operation.

Other objects and advantages of this invention will become apparent during the course of the following description.

In the accompanying drawing forming a part of this specification and in which like numerals designate like parts throughout the same,—

Fig. 1 is an elevation view of the device.

Fig. 2 is a sectional view of the device cut by a vertical plane and

Fig. 3 is a sectional view of the device cut by a horizontal plane as indicated by the line 3—3 of Fig. 2.

Referring to the drawing, 1 designates a lower member consisting of an annular ring provided with beads 2 on the peripheral edges thereof and secured within said annular member midway of its outer peripheral edges is a bottom 3.

An upper member 4 is also provided similar to the member 1 having its upper and lower peripheral edges beaded as shown at 5.

These upper and lower members 1 and 2 may be stamped or otherwise formed from aluminum or other metal as may be desired and form the nucleus of or substantially the frame work for a knock-down or collapsible drinking cup.

The body of the cup is preferably formed of a rubber tubular section 6 cut from a discarded inner tube of an automobile tire.

This section 6 may be of any desired height and in forming the upper and lower members 4 the same are stamped or formed so as to be slightly greater in diameter than the inner diameter of the section 6. Of course, the members 1 and 4 may be formed in various sizes according to the sizes of tube sections to be used in connection therewith.

In setting up the device as described the tube section of the rubber body 6 is stretched over the outer periphery of the lower member 1 so that one peripheral edge of said tube section will fit against one beaded edge thereof, as shown in the drawing. The body and bottom of the cup are thus formed and in view of the fact that the bottom member 1 is slightly greater in diameter than the inner diameter of the tube of the body section 6, these two elements will be snugly fitted together. The upper member 4 is then applied to the other end of the tube or body section 6 by spreading the end of the latter around the periphery of said member 4 until the adjacent edge fits against the one beaded edge of said member. The cup is then complete and ready for use and it will be seen that the members 1 and 2 form a rigid frame work about which the cup may be constructed. It will further be seen that the cup may be readily knocked down or collapsed by removing the upper and lower members from the body or tube section 6 and the device placed in some small convenient place in the automobile.

Tourists find it quite convenient to carry with them collapsible drinking cups, but frequently they misplace the same or the usual drinking cup found on the market is not satisfactory. By having the two end members at hand, such as illustrated and described herein, a cup may be readily formed by cutting a section from an old or discarded inner tube. Even though the body or tube section used may be lost or misplaced, a new cup may be readily formed by cutting a section from an old tube.

While I have stated that this device is used especially as a drinking cup, I wish it understood that it may be used for other purposes and I do not desire to be limited to its use as a drinking cup. Moreover, I have stated that the same is preferably made of material taken from old automobile tubes but, of course, I wish it understood that it may be made of tubular material other than automobile tubes.

It will be seen from the foregoing that I have provided a simple, inexpensive and efficient means for carrying out the objects of the invention, and while I have particularly described the elements best adapted to perform the functions set forth, it is obvious that various changes in form, proportion, and in the minor details of construction may be resorted to, without departing from the spirit or sacrificing any of the principles of the invention.

Having thus described my invention what I claim is:—

1. In a drinking cup of the class described, upper and lower annular members provided on their upper and lower peripheral edges with beads, the aforesaid lower member having a bottom formed midway of its outer peripheral edges, a tubular elastic rubber body member removably applied to the outer peripheries of said annular members and having its upper and lower peripheral edges abutting respectively the upper and lower beaded edges of said upper and lower members, the lower beaded edge of the

aforesaid lower member adapted to form a rigid base.

2. In a drinking cup of the class described, upper and lower annular members provided on their upper and lower peripheral edges with beads, the aforesaid lower member having a bottom formed midway of its outer peripheral edges, a tubular elastic rubber body member removably applied to the outer peripheries of the said annular members and having its upper and lower peripheral edges abutting respectively the upper and lower beaded edges of said upper and lower members, the lower beaded edge of the aforesaid lower member adapted to 30 form a rigid base, and means formed on the peripheral edges of said annular members at the inner opposed ends thereof for frictionally engaging the inner wall of said body member to prevent casual disengagement of the latter from the annular members when the device is assembled.

In testimony whereof I affix my signature.

WALTER S. BAKER.
